United States Patent Office

Des. 230,792

Patented Mar. 19, 1974

230,792

CHAIR

Howard I. Niederman, 3757 S. Ashland Ave.,
Chicago, Ill. 60609

Filed Jan. 3, 1972, Ser. No. 215,276

Term of patent 14 years

Int. Cl. D6—01

U.S. Cl. D6—68

FIG. 1 is a front elevational view of a chair showing my new design;

FIG. 2 is a top plan view;

FIG. 3 is a rear elevational view; and

FIG. 4 is a right side elevational view of the chair on a slightly enlarged scale, the left side being substantially a mirror image thereof.

I claim:

The ornamental design for a chair, as shown and described.
